INSULATED PICNIC JUG

Herbert M. Piker, Wyoming, Ohio, assignor to The Hamilton-Skotch Corporation, Hamilton, Ohio, a corporation of Ohio

Filed Dec. 11, 1961, Ser. No. 67,849

Term of patent 14 years

(Cl. D58—17)

FIG. 1 is a front elevational view of an insulated picnic jug showing my new design;

FIG. 2 is a side elevational view thereof;

FIG. 3 is a top plan view thereof;

FIG. 4 is a bottom plan view thereof; and

FIG. 5 is a fragmentary, sectional view thereof as seen from line 5-5 on FIG. 4.

The rear and side of the insulated picnic jug not shown are substantially the same as the front and side thereof shown in FIGS. 1 and 2.

I claim:

The ornamental design for an insulated picnic jug, substantially as shown and described.
